UNITED STATES PATENT OFFICE

EDWARD P. SHELDON, OF NEW YORK, N. Y., ASSIGNOR TO R. HOE AND CO., OF NEW YORK, N. Y., A CORPORATION OF NEW YORK.

ROTARY PRINTING-MACHINE.

1,087,191.

Specification of Letters Patent. Patented Feb. 17, 1914.

Application filed May 22, 1911. Serial No. 628,631.

To all whom it may concern:

Be it known that I, EDWARD P. SHELDON, a citizen of the United States, residing at New York, county of Kings, and State of New York, have invented certain new and useful Improvements in Rotary Printing-Machines, fully described and represented in the following specification and the accompanying drawings, forming a part of the same.

This invention relates to improvements in sheet fed rotary printing machines.

The object of the invention, generally considered, may be said to be to improve sheet fed rotary printing machines of the class in which sheets are fed to the sheet receiving cylinder in succession from a plurality of different sources or piles, the improvement being of such a character as to increase the speed of operation of such machines and to render them certain in operation and easily accessible for the purposes of "making ready," etc.

More specifically considered, the invention includes certain details of construction which while contributing to the general object above stated are in themselves applicable to sheet fed rotary machines other than those specifically referred to.

With the objects above stated and others not specifically referred to in view, the invention consists in certain constructions and in certain parts, improvements and combinations as will be hereinafter fully described and then specifically pointed out.

Referring to the accompanying drawings Figure 1 is a side elevation of so much of a rotary sheet fed printing machine embodying the invention as is necessary to an understanding thereof, the registering devices being shown as moved back to permit access to the sheet receiving cylinder. Fig. 2 is a detail sectional view on the line 2-2 of Fig. 1. Fig. 3 is a side elevation, partly in section, of certain parts of the construction shown in Fig. 1, the registering devices being in operative position. Figs. 4, 5 and 6 are detail views, and Fig. 7 is a plan view illustrating the relation of certain features of the construction.

Machines embodying the invention will include a sheet receiving cylinder. In the particular construction illustrated in the accompanying drawings, the cylinder marked 1 is the sheet receiving cylinder of a rotary

printing couple, the companion cylinder being marked 2. The cylinder 1 is mounted on a shaft 3 and the cylinder 2 on a shaft 4, the bushing of this shaft being marked 5 and the box 6. The shafts and their bearings are mounted in a side frame, indicated at 7, as is usual in such constructions.

In the best constructions embodying the invention, the sheet receiving cylinder will be provided with a single set of sheet receiving devices which may consist of ordinary grippers, indicated at 8, these grippers being mounted on a shaft 9. When, as in the particular construction selected to illustrate the invention, the sheet receiving cylinder receives the sheets on successive revolutions at different points in the revolution, the sheets being supplied from different sources, means will be provided for actuating the grippers at the sheet receiving points, which means may be varied widely in construction.

In the particular construction illustrated, the sheets are intended to be fed to the cylinder alternately from two sources on successive revolutions of the cylinder and the grippers are actuated at different points on successive revolutions. It will be understood that sheets may be fed from more than two sources, however, in which case the number of taking points for the grippers will be correspondingly increased. As shown, the mechanism for operating the grippers includes the ordinary tumbler block 10 mounted on the end of the shaft 9, the tumbler block 10 being operated by pins 11, 12 extending through openings in the frame. These pins are alternately operated by a cross-bar 13 carrying operating pins 14 engaging grooves in collars 15, 16 mounted on the pins 11, 12. The cross-bar 13 is carried on a vertical shaft secured in a bearing 17 secured to the side frame, this shaft having an operating arm 18 secured thereto which carries a follower 19 working in the groove of a cam 20 fast on the shaft 3. This cam groove is a double one, as shown in Fig. 4, with the usual cross-over in which the follower 19 works. As the follower comes up one side of the groove it crosses over at the cross-over to the other side of the groove and follows that side of the groove until the next revolution of the cylinder, when it comes up and again crosses at the cross-over to the first side of the groove. This results in operating the cross-bar 13 so as to cause

110

one of the operating pins, as 11, to come in on one revolution of the carrier, and to be thrown out on the succeeding revolution, and vice versa, as to pin 12. Each pin is therefore operated to its "in" position at alternate revolutions of the cylinder. This gripper operating mechanism, generally considered, is old in connection with presses of the two-revolution type and any other suitable mechanism may be substituted therefor.

It will be understood that suitable mechanism will be provided for opening the grippers in order to deliver the sheets, but as such mechanisms are well-understood in the art, the illustration thereof is omitted in the interest of brevity and clearness.

In the particular construction illustrated, the sheets are intended to be delivered to a delivery cylinder indicated at 25. In the particular construction illustrated, as before stated, the sheets are delivered to the sheet receiving cylinder at different points on successive revolutions of the cylinder, the sheets being obtained from any suitable sources, such, for instance, as automatic sheet feeding mechanisms, not shown.

When the invention is embodied in machines of the class indicated, the mechanism will include a plurality of sets of sheet registering devices located at or near the sheet taking points, the number of sets varying, of course, according to the number of sources from which the sheets are obtained. The particular construction of the sheet registering devices employed may be varied within wide limits, but in the best constructions embodying the invention these devices will be so constructed and mounted as to enable them to be moved back out of the way in order to afford easy access to the sheet receiving cylinder. This is particularly important in cases where the sheet receiving cylinder is, as in the construction shown, one of the cylinders of a printing couple, as in such cases ready access to the cylinder is desirable on account of "making-ready". In the particular construction illustrated, the sheets from one source are received on supporting fingers 26 mounted on a cross-bar 27 supported in arms 28 which form a part of two frames 29, these frames constituting a carriage. The sheet registering devices which coöperate with the supporting arms 26 consist of fingers 30 adjustably connected by screws 31 to arms 32 extending from a shaft 33 mounted in the carriage frames 29 (see Fig. 3). The sheets from the other source are received on supporting fingers 34 mounted on a shaft 35 supported in brackets 36 fixed to the carriage frames 29. For reasons which will be hereinafter referred to, in the best construction embodying the invention this shaft will be provided with an operating arm 37 carrying a roll 38 which runs on the usual bearer of the cylinder 1.

A spring 39 is, or may be, employed for holding the arm in such position as to cause the roll 38 to contact with the bearer. The sheet registering devices which coöperate with the support 34 include, in the construction shown, fingers 40 adjustably secured by screws 41 to an arm 42 mounted on a shaft 43 supported in the carriage frames 29 (see Fig. 3).

The carriage frames 29, in the particular construction illustrated, are provided with ribs 44 (see Fig. 2) which engage between a rib 45 formed on the side frame 7, and a rib 46 bolted to the frame 7, this construction enabling the carriage to be slid toward and away from the sheet receiving cylinder. Means may be provided for moving the carriage. While these means may be of any suitable construction, as shown each of the side frames is provided with a rack-bar 47 bolted thereto, these rack bars being engaged by pinions 48 on a shaft 49 extending across and mounted in the carriage frames 29. This shaft, as illustrated, is provided with a squared head 50 to which a wrench or crank may be applied. It is apparent that when the shaft is rotated, the carriage will be caused to travel.

It will, of course, be understood that the registering devices whatever be their construction should be so actuated as to be in operative position when the sheet is registered and then should be moved into inoperative position to permit the sheet to be taken by the sheet taking devices on the sheet receiving cylinder. The actuating mechanism employed for the registering devices may be varied within wide limits. In the best constructions embodying the invention the actuator mechanism should be common to the sets of registering devices. As shown, the actuator mechanism includes a shaft 55 supported in brackets 56 secured to the side frames. This shaft, as illustrated, is provided with a driving gear 57 meshing with a gear 58 mounted on a reduced extension of the shaft 4. The gearing should be such that the shaft is driven at a slower speed than the speed of the cylinders. As illustrated, the gearing is so proportioned as to drive the shaft 55 at one half the speed of the cylinders. This shaft 55 carries two actuating cams 59, 60 which cams, through suitable connections, operate the two sets of registering devices illustrated. The connections by which the actuator mechanism effects the operation of the registering devices may be varied, and will vary in accordance with the character of the actuator mechanism employed. In the particular construction illustrated, the operating connections include a short shaft 61 mounted in a bearing 62 (see Fig. 7) carried in a bracket 63 mounted on one of the side frames 7. Fixed to this shaft is an operating arm 64 130

having a roll 65 which runs on the cam 59. The operating connections for the other set of registering devices include a short shaft 66 mounted in a bearing 67 carried on the bracket 63. This shaft 66 is provided with an operating arm 68 which is connected by a link 69 to a short arm 70 fast on a hub or collar 71. This hub or collar is loose on the shaft 61 and has extending from it an operating arm 72 provided with a roll 73 which runs on the cam 60. Spring plungers, generally indicated at 74, may be employed, if desired, for holding the operating arms 64 and 72 down on the cams.

When the operating connections include shafts such as have been referred to, and the registering devices are also controlled from shorter shafts and when the shafts which control the registering devices are mounted, as in the construction illustrated, in the movable carriage, the connections between the shafts should be of such a character as to enable the carriage to be readily moved. As illustrated (see Figs. 5 and 6) each of the shafts 33, 48 is provided with a head 75 having a groove 76, and each of the shafts 61, 66 is provided with a head 77 having a tongue 78. In the best constructions this tongue and groove connection should be a tapered one, as shown, so that when the carriage is moved to bring the registering devices generally into operative position the tongue and groove connection may act as a stop to properly position the carriage and bring the parts into correct alignment.

When, as in the construction illustrated, the sheet receiving cylinder is one of the members of a printing couple, means should be provided for moving one of the cylinders to throw off the impression, and this means may be applied to the sheet receiving cylinder. When the throw-off means are so applied to the sheet receiving cylinder, and when the registering devices are of the class illustrated, means may be provided for shifting the position of the registering devices to prevent them from marring the surface of the sheet receiving cylinder or injuring the registering devices. The throw-off mechanism and the means referred to may, when employed, be of any suitable character. In the construction illustrated, the cylinder 1 is provided with an eccentric bearing 79 having an operating arm 80 connected with the usual operating mechanism, not shown, this throw-off mechanism being of a well understood type. In order to shift the registering mechanism, the bearing, in the construction shown, is provided with a stud 81 which, as the cylinder moves under the operation of the throw-off mechanism, contacts with a lever 82 pivoted at 83 to the frame. This lever has connected to it a rod 84 connected in turn to a bent lever 85 pivoted on the shaft 61. The forward end of this lever 85

is provided with a stud 86 extending through the lever and underlying the levers 64, 72. It is apparent that as the cylinder is thrown off, either one or the other of the levers 64, 72 will be operated according to which registering device is in operative position, and the registering device will be lifted away from the cylinder. The movement of the cylinder will also operate the arm 37 and move away the fingers 34. As the fingers 26 extend over the center of the cylinder there is no necessity for operating them when the throw-off mechanism moves the cylinder.

Changes and variations may be made in the construction by which the invention claimed is carried into effect. The invention claimed, therefore, is not to be confined to the particular construction herein described and illustrated in the accompanying drawings.

What is claimed is:—

1. The combination with a sheet receiving cylinder of a printing couple having a single set of sheet taking devices, of means for operating said devices to take sheets on successive revolutions of the cylinder at different but closely adjacent points, a plurality of sets of sheet registering devices, and an actuating mechanism common to said sets, said mechanism operating the sets of registering devices in succession to enable a sheet to be taken by the taking devices on each revolution of the cylinder.

2. The combination with a sheet receiving cylinder of a printing couple having a single set of sheet taking devices, of means for operating said taking devices to cause them to take sheets on successive revolutions of the cylinder at different but closely adjacent points, a plurality of sets of sheet registering devices, and an actuating mechanism for said registering devices including a plurality of intermittently operating cams one for each registering device, said cams causing the registering devices to operate in succession to enable a sheet to be taken by the taking devices on each revolution of the cylinder.

3. The combination with a sheet receiving cylinder of a printing couple having a single set of sheet taking devices, of means for operating said devices to cause them to take sheets at different but closely adjacent points on successive revolutions of the cylinder, a plurality of sets of sheet registering devices, said devices including suitable sheet stops located at the sheet taking points, and an actuating mechanism common to said sets, said mechanism operating to withdraw the stops successively.

4. The combination with the sheet receiving cylinder of a rotary printing couple, said cylinder having a single set of sheet taking devices, of means for operating

the taking devices to cause them to take a sheet on successive revolutions of the cylinder, a plurality of sets of sheet registering devices located over the cylinder, said devices including suitable front stops, operating shafts for said stops, a carriage in which the shafts and the stops are mounted, an actuating mechanism for the shafts, and detachable connections between the shafts and the actuating mechanism.

5. The combination with the sheet receiving cylinder of a rotary printing couple, said cylinder having a single set of sheet taking devices, of a plurality of sets of sheet 15 registering devices located over the cylinder, an operating shaft for each set, a carriage in which said sets and shafts are mounted, a plurality of actuating cams located above the cylinder, connections between the cams 20 and the shafts, and means for detachably connecting the shafts and the connections.

6. The combination with the sheet receiving cylinder of a rotary printing couple, said cylinder having a single set of sheet 25 taking devices arranged to take sheets at different but closely adjacent points on successive revolutions of the cylinder, of a carriage, a plurality of rock-shafts mounted in the carriage, and a plurality of sets of sheet 30 stops operated from the shafts.

7. The combination with a sheet receiving cylinder having sheet taking devices, of a sheet registering mechanism located over the cylinder, said mechanism including an 35 operating shaft, a carriage in which said registering mechanism and shaft are mounted, a frame in which the carriage moves, an actuating mechanism for the shaft mounted in part in the frame, and detachable connections directly connecting the operating 40 shaft and the parts of the actuating mechanism mounted in the frame.

8. The combination with a sheet receiving cylinder having sheet taking devices, of 45 a registering mechanism including an operating shaft, a carriage in which said shaft is mounted, a frame in which the carriage moves, a short shaft extending through the frame, said short shaft being directly and 50 detachably connected to the operating shaft, an actuator, and operating connections between the actuator and the short shaft.

9. The combination with the sheet receiving cylinder of a rotary printing couple, 55 said cylinder having a single set of sheet taking devices, of means for causing said devices to take a sheet on successive revolutions of the cylinder at closely adjacent points, two sets of sheet registering devices, 60 each set including an operating rock-shaft, a carriage in which said rock shafts are mounted, a frame in which the carriage moves, short actuating shafts extending through the frame, said short shafts being 65 detachably connected to the operating

shafts, an actuator including a plurality of intermittently operated cams, and operating connections between the short shafts and the cams.

10. The combination with the sheet receiving cylinder of a rotary printing couple, 70 said cylinder having a single set of sheet taking devices, of means for operating said devices to take a sheet on successive revolutions at different but closely adjacent points, 75 a plurality of sets of sheet registering devices located over the cylinder, each set including sheet stops and an operating shaft for said stops, a carriage in which said shafts and registering devices are mounted, a frame in which the carriage moves, short 80 actuating shafts extending through the frame, said shafts being detachably connected to the operating shafts, an actuator mechanism including a plurality of intermittently 85 operated actuating cams one for each set of registering devices, and operating connections between the cams and actuating shafts.

11. The combination with a sheet receiving cylinder, of a sheet registering mechanism including front stops located over the cylinder, an operating shaft, a carriage in which the operating shaft is mounted, a frame in which the carriage moves, a short 90 actuating shaft, a tongue and groove connection between the operating shaft and the actuating shaft, and means for operating the actuating shaft.

12. The combination with a sheet receiving cylinder, of a sheet registering mechanism including front stops located over the cylinder, an operating shaft, a carriage in which the operating shaft is mounted, a frame in which the carriage moves, a short 95 actuating shaft, a tapered tongue and groove connection between the operating shaft and the actuating shaft, and means for operating the actuating shaft.

13. The combination with a sheet receiving cylinder, of two sets of sheet registering devices located at different points in the revolution of the cylinder, actuating mechanism for operating said sets successively, a throw-off mechanism for the cylinder, and 110 connections whereby a set of the registering devices may be shifted when the cylinder is thrown off.

14. The combination with a sheet receiving cylinder having a plurality of sets of sheet registering devices, of means for operating said devices in succession, a throw-off mechanism for the cylinder, and means operated by the movement of the cylinder for shifting the position of either set of registering devices.

15. The combination with a sheet receiving cylinder having a single set of sheet taking devices, of means for operating said devices to cause them to take sheets on succe- 130

sive revolutions of the cylinder, two sets of sheet registering devices at different sheet taking points, means for operating said sets in succession, a throw-off mechanism for the cylinder, and means operated by the movement of the cylinder for shifting either set of sheet registering devices.

16. The combination with a sheet receiving cylinder having a single set of sheet taking devices, of means for operating said devices to cause them to take sheets at different points in successive revolutions of the cylinder, a plurality of sets of sheet registering devices one at each sheet taking point, a throw-off mechanism for the cylinder, and means operated by the movement of the cylinder as it is thrown off for shifting the position of any set of registering devices which is in operative position at the time the cylinder moves.

17. The combination with a sheet receiving cylinder having a single set of sheet taking devices, of means for operating said devices to cause them to take sheets at different points in the revolution of the cylinder on successive revolutions of the cylinder, a plurality of sets of registering devices, one set at each sheet taking point, each of said sets including sheet stops and an operating rock-
25 shaft therefor, a throw-off for the cylinder, and means operated by the movement of the cylinder for rocking the shafts to shift the position of the stops when the cylinder is thrown off.

30 18. The combination with a sheet receiving cylinder having a single set of sheet tak-

ing devices, of means for operating said devices to take a sheet on successive revolutions of the cylinder, a plurality of sets of sheet registering devices, each set including 40 sheet stops and an operating shaft for said stops, a carriage in which said registering devices and shafts are mounted, a frame in which the carriage moves, and an actuating mechanism including operating levers 45 located outside the frame for operating the shafts.

19. The combination with the sheet receiving cylinder of a rotary printing couple, said cylinder having a single set of sheet taking devices, of means for operating said devices to take a sheet on successive revolutions of the cylinder, a plurality of sets of sheet registering devices, each set including sheet stops and an operating shaft for said stops, 50 a carriage in which said shafts and registering devices are mounted, a frame in which the carriage moves, short actuating shafts extending through the frame, said shafts being detachably connected to the operating shafts, and an actuating mechanism including operating connections for the short shafts, said connections being located outside the frame.

In testimony whereof, I have hereunto set 65 my hand, in the presence of two subscribing witnesses.

EDWARD P. SHELDON.
